UNITED STATES PATENT OFFICE.

EDWARD B. MANNING, OF MERIDEN, CONNECTICUT, AND HENRY A. MANNING, OF NEW YORK, N. Y.

FILTER FOR COFFEE-POTS.

SPECIFICATION forming part of Letters Patent No. 307,969, dated November 11, 1884.

Application filed November 3, 1883. (No model.)

To all whom it may concern:

Be it known that we, EDWARD B. MANNING, of Meriden, county of New Haven, and State of Connecticut, and HENRY A. MANNING, of New York, in the county of New York and State of New York, have invented a new Improvement in Filters for Coffee-Pots; and we do hereby declare the following, when taken in connection with accompanying drawings and the letters of reference marked thereon, to be a full, clear, and exact description of the same, and which said drawings constitute part of this specification, and represent, in—

Figure 1, a sectional side view of a coffee-pot with the filter in place; Fig. 2, a diagram illustrating the method of cutting the blanks to form the bag; Figs. 3 and 4, perspective views showing the method of stitching up the bag; Fig. 5, a diagram illustrating the modification of the cut; Fig. 6, a side view of the bag complete; Fig. 7, the divided ring detached.

This invention relates to a device for use in coffee-pots to hold the ground coffee in the upper part of the pot, so that water may be poured thereon and run through into the pot below, commonly called "filters," and particularly to filters which are made from fabric and of bag-like character, the object of the invention being to provide the pot with an internal bottomless cup combined with a fabric bag at the bottom of the cup; and it consists in the construction of the bottomless cup and bag, as more fully hereinafter described, and particularly recited in the claim, whereby the bag may be readily attached or detached from the bottomless cup.

Preferably we make the filtering-bag in one piece. We cut the blank in T shape, as seen in Fig. 2, A, or the upright of the T, representing the bottom of the bag, and the cross that part which will form the body. The upright is cut substantially square, and the projections B B, each side, in length correspond each to one of the sides, and little more than half of the third side. The blank thus cut, the cross portion is turned up at right angles to the bottom A, as seen in Fig. 3. Then the projections B are bent around the bottom, and the lower edge stitched to the respective sides of the bottom, the two ends of the cross brought together and stitched, as at a, Fig. 4, which completes the bag, and makes practically a square bag.

Instead of making the cut in T shape, it

may be L-shaped, as seen in Fig. 5, the longer side B turned up and carried around the three sides of the bottom and joined at b, with the same result.

The filter or bag is usually attached to a bottomless cup to be set into the top of the pot. C represents this cup. Upon the outside of the cup, near the lower end, an annular groove, d, is formed. Into the upper edge of the bag D a divided ring, E, is introduced. This may be done by inclosing the ring in the upper edge of the bag, as seen in Fig. 6. The diameter of this ring (see Fig. 7) in its normal condition is less than the external diameter of the cup C; but because of its being cut it yields so as to be passed on over the end of the cup until it arrives in the groove d, where it automatically contracts and embraces the cup with sufficient force to hold the bag to the cup, but yet allow of its removal for cleansing or other purposes. By this construction we produce a cheap and durable filter, and one which may be readily cleansed.

We are aware that filters for coffee-pots have been made consisting of a bottomless cup and a fabric bag attached thereto; and we are also aware that a divided ring, broadly considered, has been employed to support a cloth bag inside a coffee-pot; but we do not claim either of these features, broadly; neither do we make claim to the method of cutting the bag, but simply show it as a convenient method of so doing.

We claim—

A filter for coffee-pots, consisting of the bottomless cup C, constructed with an annular groove, d, upon its outer surface near its lower end, combined with the fabric bag D, provided with the divided elastic self-contracting metal wire ring E, introduced into its upper edge, and corresponding substantially to the groove d in the cup, and whereby the upper edge of the bag inclosing the ring may be placed over the lower end of the cup, and the divided ring contract to engage the groove d in the cup, substantially as described.

EDWARD B. MANNING.
